UNITED STATES PATENT OFFICE.

CHARLES M. STEIN, OF PARIS, FRANCE.

AUTOMATIC OBTURATOR FOR THE SUPPLY PIPE FOR BURNERS.

Application filed May 11, 1922, Serial No. 560,152, and in France May 14, 1921.

In his application for United States patent, Serial No. 560,151, filed May 11, 1922, for a safety device for burners fed with gaseous or powdered solid combustible, the applicant has referred to the danger which may be caused by the return of the flame in pipes for feeding burners and containing a current of air charged with powdered combustible or simply a combustible gas. In order to obviate this danger of the return of the flame the applicant has suggested a safety device comprising a constriction of the pipe which by increasing the velocity of the flow will momentarily stabilize the returning flame even if the volume be reduced and will thereby enable an obturator to be interposed for the purpose of definitively isolating the flame from the reserve combustible.

This invention has for its object a method of automatic obturation adapted for use with a safety device of the same type. As in the case of the application referred to above this obturator is released at the required moment by the destruction of a readily combustible connection through the effect of the return of the flame.

The accompanying drawings show by way of example two methods of construction of this obturator in which the rupture of the connection has the effect of cutting off the current passing through an electro-magnet and thereby causing an isolating valve to be closed.

In these two forms of construction it is assumed that powdered combustible suspended in air is being distributed through a closed conduit.

The parts common to the two installations represented diagrammatically in Figures 1 and 2 are designated by the same reference letters.

In Figure 1, 1 represents the distribution conduit and 2 is the branch pipe for feeding the burner 3. It is this branch which must be completely closed in the event of the flame returning towards the main conduit.

For this purpose a conical valve 4 which is guided vertically may be caused to move on to its seat 5, the valve casing being placed in communication with the branch pipe 2 on the main conduit 1. The closing and the opening of the valve is effected by the fall and rise respectively of the armature of an electro-magnet 6 connected with a branch circuit from the main cables 7 that serve all

the furnaces. As long as current is passing through the electro-magnet, that is to say, in normal working, the armature of the electro-magnet remains in its upper position and maintains the counterweight 8 raised. In this position, the valve 4 is held open by the lever 9, which is pivoted at the fixed point 10, and the link 11. If for any reason the current no longer passes through the solenoid 65 the armature falls and the counterweight 8 presses the valve 4 firmly on its seat 5.

It will be obvious that if the current passing through the cables 7 is taken from the circuit of the motor for the distribution fan 70 any voluntary or accidental stoppage of the said motor will cause the immediate closing of all the isolating valves.

But the most important function of the obturating device described above is the closing of the conduit in the event of the return of the flame which constitutes a grave danger. At 12 there is inserted in the branch piping the before-mentioned special safety device comprising a constriction formed by 80 the junction of two divergent cones. In the event of the return of the flame the acceleration of the flow of the gases in the upper cone insures the stabilization of the said flame in the lower cone for some time. At the base 85 of the lower cone a wire 13, which is attached to a fixed point by an instantaneously combustible connection 14, holds an automatic cut-out 15 in the closed position. When the connection 14 is consumed the cut- 90 out 15 is released by the spring 16 and cuts off the current in the electro-magnet 6, thereby ensuring the closing of the main conduit as hereinbefore described.

In addition there may be provided an ordinary hand switch 17 which, when operated by the workman, will enable any one of the series of furnaces to be isolated at will.

In Figure 2 there is shown a modified method of operating the isolating valve 4 100 by breaking the circuit in an electro-magnet 18. The valve 4 is still guided vertically by its rod and is suspended by the link 11 from a lever 9 which is pivoted at a fixed point 10. A spring 19 takes the place of the counterweight 8 in the first construction and constantly tends to pull the valve 4 on to its seat 5. The end 9^a of the lever 9 engages with the end 20^a of the lever 20 that is pivoted at the fixed point 21 so long as the current flows through the solenoid 18, that is to say, so long as the burner is allowed to re-

main in communication with the source of powdered coal. But if for one of the reasons already indicated, viz, a breakage of the circuit; a voluntary interruption by the workman, or a return of the flame; the current is interrupted in the electromagnet 18 so that it no longer pulls the end of the lever 20, the opposing spring 22 will cause the disengagement of the levers 9 and 20 and the released spring 19 will effect the closing of the branch.

By pulling the small chains which are provided with handles 23 and 24 and of which one is attached to an arm on the lever 20 and the other to a prolongation of the lever 9 it is possible to re-set the device after its operation. For this purpose the ends of the levers 9 and 20 are provided at 9^a and 20^a with suitable ramps which are capable of sliding one on the other. On the other hand the engagement cannot be effected by operating the handles 23 and 24 unless the current is again circulating through the solenoid to neutralize the action of the spring 22 and maintain the lever 20 in the proper position for engagement.

I claim—

1. A device for preventing the passage of flame through a pipe comprising a closure for the pipe, an electrically actuated instrument normally holding the closure in inoperative position, and a non-electric conducting member situated to be acted upon by the flame to cause a change in the electrical conditions of the instrument thereby to allow the closure to close the pipe.

2. A device for preventing the passage of flame through a pipe, comprising a closure for the pipe, an electrically actuated instrument normally holding the closure in inoperative position, automatically moving means to change the electrical conditions of the instrument to allow the closure to close the pipe, a combustible member normally holding said means in a given position and situated to be acted upon by the flame to cause such movement of said means as will cause the actuation of the instrument to permit closure of the pipe, and an element for actuating the device to cause the closure to close the pipe irrespective of said automatic means.

3. The combination with a combustible

material conveying pipe shaped to retard the passage of flame therethrough, of a closure for the pipe, an electrically actuated instrument normally holding the closure in inoperative position, a member situated to be acted upon by the retarded flame to cause a change in the electrical conditions of the instrument, thereby to permit the closure to close the pipe, and an element for actuating the device to cause the closure to close the pipe irrespective of said member.

4. A device for preventing the flare-back of flame through a pipe comprising a closure for the pipe, an electrically actuated instrument normally holding the closure in inoperative position and a member situated to be acted upon by the flame to cause a change in the electrical conditions of the instrument thereby to allow the closure to close the pipe.

5. A device for preventing the passage of flame through a pipe comprising a closure for the pipe, an electrically actuated instrument holding the closure in inoperative position, and a fusible member situated in the path taken by the flame during the flare-back to be acted upon by the flame to cause a change in the electrical conditions of the instrument thereby to allow the closure to close the pipe.

6. A device for preventing the passage of flame through a pipe comprising a closure for the pipe, an electrically actuated instrument normally holding the closure in inoperative position, and a member situated in the path taken by the flame during the flare-back and at a point between the closure and the point at which the flare-back begins, to be acted upon by the flame to cause a change in the electrical conditions of the instrument thereby to allow the closure to close the pipe.

7. A device for preventing the passage of flame through a pipe comprising a closure for the pipe, an electrically actuated instrument normally holding the closure in inoperative position and a combustible member situated within the pipe to burn upon contact with the flame to cause a change in the electrical conditions of the instrument, thereby to allow the closure to close the pipe.

In testimony whereof I have signed my name to this specification.

CHARLES M. STEIN.
